INVENTOR
Joseph Hirshstein
BY *E. E. Huffman*
ATTORNEY

UNITED STATES PATENT OFFICE.

JOSEPH HIRSHSTEIN, OF CLEVELAND, OHIO.

VENT-PIPE SLEEVE.

Application filed May 16, 1923. Serial No. 639,286.

To all whom it may concern:

Be it known that I, JOSEPH HIRSHSTEIN, a citizen of the United States of America, residing at the city of Cleveland, county of Cuyahoga, State of Ohio, United States of America, have invented a certain new and useful Vent-Pipe Sleeve, of which the following is such a full, clear, and exact description as will enable any one skilled in the art to which it appertains to make and use the same, reference being had to the accompanying drawings, forming part of this specification.

My invention relates to a flashing sleeve for vent pipes or the like, which pass through roofs or other surfaces. Its object is to produce a sleeve embodying convenient and effective means for making water-tight adjustable clamping connection between it and a surrounding flashing or the waterproofing material on the roof.

In the accompanying drawing Figure 1 is a cross-sectional view showing one embodiment of my invention, and Figure 2 is a top plan view of the device illustrated in Figure 1.

My improved vent pipe sleeve 1 surrounds the vent pipe 2, and an annular recess 3 on the inner wall of the sleeve forms a space between the pipe and the sleeve for the insertion of suitable packing material.

The sleeve 1 is provided with an integral exterior flashing flange 4 over which the flashing or waterproofing material 5 may be extended. Sleeve 1 is also provided with a terminal locking flange 6, which flange has spaced openings 7 therethrough. The flashing clamping ring 8 of annular shape and having sufficient internal diameter to pass over the terminal flange 6, bears upon the upper surface of the flashing which is clamped between it and the flashing flange 4 to form a water-tight union between the flashing and the sleeve. The clamping ring 8 is provided with inwardly extending lugs 12 which cooperate with the exterior of the sleeve to properly position the opposing surfaces of the ring and flashing flange. These pass through openings 7 in the terminal flange 6 in the assembling of the parts.

Clamping pressure is applied to the clamping ring 8 by means of the threaded bolts 9 carried by locking ring 10. This

locking ring is also annular, having internal diameter slightly greater than the diameter of the terminal flange 6, but is provided with integral inwardly projecting lugs 11, which, while they are adapted to pass through openings 7 in the terminal flange, bear upon the under surface of this flange when the locking ring is rotated after application to the sleeve, and the clamping bolts have been screwed down to apply clamping pressure to the ring 8.

As above indicated the waterproofing material 5 may either be a flashing positioned in the material of the roof below the upper surface thereof, or may be a sheet of waterproofing material such as paper, felt or the like, which constitutes the top surface of the roof.

The arrangement described is rigid and reliable and permits the ready clamping in position of waterproofing material of varying thicknesses. It also allows of the positioning of the clamping bolts in the position which may be most convenient in the particular installation being made.

Having fully described my invention, what I claim as new and desire to secure by Letters Patent of the United States is:

1. The combination of a pipe sleeve provided with a flashing flange and a locking flange, a clamping ring cooperating with the flashing flange, a locking ring above the clamping ring and having portions engaging the locking flange, and clamping bolts in threaded engagement with the locking ring and bearing on the clamping ring.

2. The combination of a pipe sleeve provided with an exterior circumferential flashing flange intermediate its ends, a clamping ring cooperating with said flange, and means engaging the sleeve above the flashing flange for holding said ring in clamping position.

3. The combination of a pipe sleeve provided with an exterior circumferential flashing flange intermediate its ends, a clamping ring cooperating with said flange, and locking ring engaging the sleeve above the flashing flange for holding said ring in clamping position.

4. The combination of a pipe sleeve provided with a flashing flange and a locking flange, said locking flange having spaced

openings therethrough, a clamping ring co-operating with the flashing flange, a locking ring rotatable with respect to the sleeve and having inwardly projecting lugs adapted to pass through the openings in the locking flange and to be brought into opposition with the under surface of said flange by ro-

tative movement of the locking ring, and adjustable means extending from the locking ring to the clamping ring to force the latter into clamping position.

In testimony whereof, I have hereunto set my hand and affixed my seal.

JOS. HIRSHSTEIN. [L. S.]
